UNITED STATES PATENT OFFICE.

MAURICE J. WOHL, OF NEW YORK, N. Y., ASSIGNOR TO M. J. WOHL & CO., INC., OF LONG ISLAND CITY, NEW YORK, A CORPORATION OF NEW YORK.

ELECTRIC-ARC LAMP.

Application filed October 7, 1920. Serial No. 415,295.

To all whom it may concern:

Be it known that I, MAURICE J. WOHL, a citizen of the United States, and residing at New York city, in the county of Queens and 5 State of New York, have invented certain new and useful Improvements in Electric-Arc Lamps, of which the following is a specification.

This invention relates to improvements in 10 electric arc lamps and especially to that type in which a plurality of arcs are simultaneously employed for photographic illumination or similar purposes.

It is the particular object of the present 15 invention to provide a lamp which is light in weight, operates the carbon electrodes vertically as required for photo work and embodies a minimum of moving parts, assuring reliable operation.

20 It is a further object of the invention to provide a lamp in which two or more arcs are arranged in series and regulated by a single operating element without a complex gear transmission mechanism.

25 With these and other objects in view the invention consists of a novel arrangement of parts and details of construction herein-after fully described and illustrated by the accompanying drawings and finally pointed 30 out in the claims.

In the drawings which form a part of these specifications:

Fig. 1. is a side elevation of an arc lamp for two arcs in series in which the two pairs 35 of carbon electrodes are arranged parallel to each other. The side cover plate and a part of the reflector are removed to show the mechanism, and some parts are broken away for better illustration.

40 Fig. 2. is a sectional plan of the same lamp on the line 2-2 of Fig. 1. The reflector is omitted in this figure.

Fig. 3. is a front elevation of the same lamp as seen from the right of Figures 1 45 and 2.

Fig. 4. is a side elevation of a lamp for three arcs in series in which two pairs of carbon electrodes are arranged above each other in a straight line.

50 Fig. 5. is a sectional plan of the same lamp taken on line 5-5 of Fig. 4.

Fig. 6. is a detail of one of the elastic links 23 showing its attachment to lever 18 and clutch 24.

55 Fig. 7. is a side elevation of Fig. 6.

Referring to Figs. 1 and 4 the lamp consists of a base plate 1 which supports, by means of vertical bars 2 and 3, a horizontal plate 4 on which bracket 5 forming a fulcrum support for pin 7 of forked lever 6 is 60 mounted. The smaller (rear) fork 8 of lever 6 is pivotally connected by means of pivot 9 to the plunger-stem 10 of dashpot 11. The lower end of stem 10 holds a bracket 12 which supports a horizontal 65 spring 13; to this spring the core 14 of solenoid 15 is fastened in axial alinement therewith and with dash-pot 11, which is suitably supported above the solenoid. A resistance coil 16 is mounted above the dash- 70 pot, depending from the top plate 17 of the lamp housing. The larger, (front) fork 18 of lever 6 is provided with a plurality of pivot pins, 20, 21, (and 22 for the lamp with three arcs shown in Fig. 4,) the distances of these pins from the fulcrum 7 are 75 multiples of the distance between pivot 9 and fulcrum 7. In other words the distance from 7 to 20 is equal to the distance from 7 to 9, while the distance from 7 to 21 is 80 twice, and from 7 to 22 three times the distance from 7 to 9 for the respective lamps. From each of the pins 20-21-22 depends a 85 pair of elastic links 23 which operate the clutches 24-25-26 of the familiar hinged type which rest in their lowest position on plate 4. In Fig. 1 the clutch 24 is arranged to operate by lifting, a tubular sleeve 27 and clutch 25 a similar sleeve 28. These sleeves pass freely through plate 4 and are guided 90 on rods 29 and 30 which are arranged between plates 1 and 17 of the lamp housing.

The lamp shown in Figs. 1 to 3 is equipped with two pairs of carbon electrodes arranged parallel to each other; current enters the lamp through terminal 31, passes through solenoid 15 and resistance coil 16 to the carbon holder 33 and electrode 34 which is held by, but insulated from, curved arm 35. This arm is fastened to the upper end of sleeve 28 which is prevented from turning horizontally by arm 36 guided on rod 2. The negative electrode 37 of this pair of carbons (see Fig. 3) and the positive electrode of the second pair are held by carbon holders 38 and 41, and both carried on a vertical rod 43 by means of the arms 39 and 40 which are rotatively held thereon. Rod 43 is provided with a deflector blade 44 and is rotatively held by 100 105 110

holder 45 which is carried by, but insulated from arm 46, fastened to the upper end of sleeve 27. Arm 46 is guided on rod 30 to prevent horizontal motion. The negative carbon electrode 47 is held in holder 48 which is held stationary by, but insulated from arm 49 of bottom plate 1.

The lamp housing is provided with a suitable reflector 70 and trunnions 71 held on side plates 72 which permit swiveling of the lamps in a suitable stand angularly, while the rear cover plate 73 is provided with a suitable handle 74 for the convenience of the operator.

15. The novel operation of these lamps consists primarily in the arrangement of the clutches to lift their sleeves proportionally different distances while the electrodes are so arranged that the lengths of all arcs remain equal.

When no current passes through the lamp (Fig. 4) all clutches close their blades resting on plate 4 and the carbon electrodes fall together by gravity. When current passes through the solenoid 15, lever 8 is lifted, and with the same clutches 24-25-26 raise their sleeves 65-62-52 and the carbon holders attached thereto in proportional distances, which means that carbon holder 60 is raised twice as much, and 50 three times as much as 63. The distances between the electrodes 59-58, 58-57 and 57-56 remain always equal as they are produced by the difference of motion. In the lamp of Figs. 1 to 3 the same principle is applied with the modification that the two arcs are arranged side by side. In this case electrodes 37 and 42 are lifted the same distance by clutch 24 while 34 is lifted twice as much by clutch 25 which results in an equal length of the arcs between 47-42 and 37-34. It is evident that to each one of the arms 35, 39, 40 and 49 a second carbon holder could be attached and four pairs of carbons be operated by the same mechanism. This invention provides many advantages over attempts heretofore made to operate a plurality of arcs from the same solenoid as it eliminates all gearing with a corresponding reduction in weight and friction. It provides the vertical arrangement of electrodes for photographic illumination where specific direction of the light is essential. Another advantage is to be found in the fact that there is only a single traveling flexible connection to the positive carbon holder necessary.

Where three arcs are arranged above each other an advantage is gained in current consumption on 125 volts and only one shadow perceptible in the horizontal plane.

Having thus described my invention what I claim as new and desire to secure by Letters Patent is:

1. In an arc lamp a plurality of electrodes

arranged in a single vertical line, a fixed electrode forming one end of said line, means mounting said plurality of electrodes to move toward and away from said fixed electrode to form a plurality of arcs, a clutch for each movable electrode to operate the same and common means joining all clutches to move them and the electrodes simultaneously through distances forming multiples of the movement of the clutch for the electrode nearest the fixed electrode to form arcs of equal length between the electrodes.

2. In an arc lamp a fixed electrode and a plurality of other electrodes, means mounting said electrodes in a single straight line, said fixed electrode forming one end of said line, clutches forming means to separate the electrodes, a single magnetic means operating common means for all clutches, said common means being connected to said clutches to move them and said other electrodes simultaneously through distances which form multiples of the opening of the clutch for the electrode nearest the fixed electrode to produce openings of equal length between the electrodes.

3. In an arc lamp a fixed electrode and a plurality of other electrodes held in axial alignment therewith and means mounting the electrodes to move the other electrodes toward and away from said stationary electrode in the same direction, holders for the movable electrodes and means to move all holders with their electrodes simultaneously throughout their whole movement, said means being adapted to move the other electrodes through multiples of the distance through which the first movable electrode is moved away from the fixed electrode.

4. In an arc lamp a single stationary electrode, a plurality of other electrodes held in axial alignment therewith and means mounting the electrodes to move them toward and away from said stationary electrode in the same direction, holders for said movable electrodes, gravity operated arms carrying said holders, clutches adapted to lift all of said arms and common means to lift said clutches, said arms and electrodes simultaneously throughout their whole movement through multiples of the distance through which the electrode next to the stationary electrode is lifted.

5. In an arc lamp a plurality of electrodes arranged in series with each other, one electrode forming the end of the series being fixed, means mounting the electrodes to move all other electrodes in the same direction away from said fixed electrode to form arcs between the free ends of all electrodes, and common means to separate the movable electrodes simultaneously distances which are multiples of the length of the arc opening at the fixed electrode.

6. In an arc lamp a frame, a plurality of

electrodes arranged on said frame in a series circuit, one electrode of said series being fixed to said frame, means to move the other electrodes toward and away from said fixed electrode, said means including a clutch for each one of said movable electrodes, and common means to open said clutches simultaneously amounts which differ in multiples of the clutch opening for the electrode nearest said pivot.

10 est the fixed electrode.

7. In an electric arc lamp, a single stationary and a plurality of other electrodes, and means mounting the electrodes to move the other electrodes in the same direction simultaneously through distances forming multiples of the arc opening at the stationary electrode to maintain arcs of equal length between the electrodes.

8. In an electric arc lamp a plurality of electrodes including a single stationary electrode, means mounting the electrodes to move

toward and away from each other and from said stationary electrode in the same direction; magnetic means arranged to operate parallel to said electrodes to one side thereof, clutches to lift the movable electrodes and means between said magnetic means and said clutches to lift each clutch a distance forming a multiple of the lift of the clutch nearest said pivot.

25

9. In an electric arc lamp a frame, a plurality of electrodes movably held on said frame, a single electrode fixed to said frame, clutches to operate the movable electrodes, a lever holding all clutches on one side of its fulcrum at distances which form multiples of the distance between said fulcrum and the clutch nearest thereto and magnetic means to operate said lever at the other side of its fulcrum.
